United States Patent Office

Des. 185,615
Patented June 30, 1959

185,615

WARNING REFLECTOR

Friedrich Reinholdt, College Point, N.Y.

Application October 8, 1958, Serial No. 52,905

Term of patent 14 years

(Cl. D72—1)

FIG. 1

FIG. 2

FIG. 3

FIG. 4

Fig. 1 is a plan view of a warning reflector showing my new design;

Fig. 2 is a side view of Fig. 1;

Fig. 3 is a plan view of another side thereof; and

Fig. 4 is an end view of Fig. 1.

I claim:

The ornamental design for a warning reflector, substantially as shown.
